(57) **CLAIM**

The ornamental design for a “distributor plate,” as shown and described.

DESCRIPTION

FIG. 1 is a front elevational view of the “distributor plate” design according to our invention;

FIG. 2 is a back elevational view of the “distributor plate” shown in FIG. 1;

FIG. 3 is a right elevational view of the “distributor plate” shown in FIG. 1;

FIG. 4 is a left elevational view of the “distributor plate” shown in FIG. 1;

FIG. 5 is a top view of the “distributor plate” shown in FIG. 1;

FIG. 6 is a bottom view of the “distributor plate” shown in FIG. 1.

FIG. 7 is a top perspective view of the “distributor plate” shown in FIG. 1.

FIG. 8 is a bottom perspective view of the “distributor plate” shown in FIG. 1.

FIG. 9 is a side perspective cross sectional view of the “distributor plate” shown in FIG. 1.

FIG. 10 is a top front perspective view of the “distributor plate” shown in FIG. 1; and,

FIG. 11 is the enlarged area of the “distributor plate” shown in FIG. 10.

In the drawings, the dot-dashed lines represent unclaimed boundaries and form no part of the claim.
